UNITED STATES PATENT OFFICE.

ALBERT J. GURNEY, OF CANTON, OHIO, ASSIGNOR TO THE AMERICAN MINE DOOR CO.,
OF CANTON, OHIO, A CORPORATION OF OHIO.

WIRE HANGER.

Application filed June 14, 1924. Serial No. 720,073.

To all whom it may concern:

Be it known that I, ALBERT J. GURNEY, a citizen of the United States, residing at Canton, in the county of Stark and State 5 of Ohio, have invented certain new and useful Improvements in Wire Hangers, of which the following is a specification.

This invention relates to an improved hanger for trolley wires, signal wires, feed 10 wires, or the like, being of the general character shown in my co-pending application for wire hanger, filed November 7, 1923, Serial No. 673,332, and seeks to provide a device of this character embodying 15 a pair of mating jaws; wherein, in use, one of the jaws may be mounted upon a support for the hanger when the other of the jaws may be assembled with the former jaw for clamping the wires between the jaws to 20 be suspended by the hanger, and wherein in the latter jaw will be provided with means coacting with the former jaw for centering the jaws and locking said jaws against relative movement when assembled.

25 And the invention further seeks to provide a two-wire hanger particularly adapted for use as a unit hanger for both a trolley wire and a feed wire and wherein the hanger will provide an electrical connection between the wires for conducting current from the feed wire to the trolley wire.

Other and incidental objects will appear hereinafter.

In the drawings:

35 Figure 1 is a side elevation of my improved hanger, parts being broken away and illustrated in section,

40 Figure 2 is a detail sectional view on the line 2—2 of Figure 1, looking in the direction of the arrows,

Figure 3 is a detail sectional view on the line 3—3 of Figure 1, looking in the direction of the arrows,

45 Figure 4 is a detail elevation looking at the inner side of one of the jaws, and

Figure 5 is a view similar to Figure 3 showing the use of the device without a tubular insulator for supporting a feed wire in conjunction with a trolley wire.

50 In carrying the invention into effect, I employ a pair of mating oblong jaws 10 and 11 grooved at their lower margins, as at 12, to receive a wire therebetween, as for instance, a trolley wire, as conventionally illustrated at 13. Above the groove 12, the

jaws are formed with complementary semi-cylindrical barrel portions 14 mating to provide a closed barrel having end wall portions 15 from which extend the mating halves of tapered nipples 16. Rising from the jaw 10 medially thereof is an internally threaded sleeve 17 lying, as particularly shown in Figure 4, partially within the barrel portion 14 of said jaw, and extending transversely of said barrel portion from the base of the sleeve is a pair of semi-circular reinforcing webs 18 disposed in parallel relation. Rising from the jaw 11 to fit about the sleeve 17 is a semi-cylindrical flange or half-collar 19 and extending transversely within the barrel portion of said jaw is a pair of reinforcing webs 20 like the webs 18 and registering therewith. Formed on the end wall portions of the jaw 10 are pairs of centering lugs 21 disposed above and below the halves of the nipples 16 on said end wall portions to project, as shown in Figure 2, into the barrel portion of the jaw 11 abutting the end wall portions of the latter jaw at their inner 70 sides. However, these lugs may, for convenience, be formed on the jaw 11 and will serve to rigidly lock the jaws against relative movement. Screwed upon the nipples 16 are nuts 22 clamping the jaws together. 75 As shown, the pairs of webs 18 and 20 are notched to snugly accommodate a tubular insulator 23 extending through the nipples 16 so that the insulator is thus supported medially by said webs and, as will be observed, the insulator is adapted to receive a signal wire or the like, therethrough, as conventionally shown at 24.

Attention is now particularly directed to the fact that in any instance where a feed wire, as shown at 24^a in Fig. 5, is to be supported in conjunction with the trolley wire 13, the insulator 23 is eliminated when the device will provide a highly satisfactory and efficient unit for suspending both wires. 95 In such instance, the wire 24^a will, as will be seen, be confined between the jaws of the device to directly contact said jaws so that the hanger will thus provide a direct electrical connection between the wires. Accordingly, the current will be fed from the wire 24^a to the wire 13 at each hanger throughout a trolley line so that the voltage will be equalized while, should the trolley wire break, the current will continue 100 105 110

through the feed wire to the hangers beyond the break to be again fed to the trolley wire so that the presence of the break in the trolley wire will not interrupt the current supply. At the same time, an economical installation is provided since the necessity for separate hangers for the feed wire is eliminated.

In use, a supporting insulator, as conventionally shown at 25, will preferably be provided in conjunction with the hanger. This insulator may be of any approved type but will include a threaded stud 26 projecting from the lower end of the insulator to receive the sleeve 17 of the jaw 10 of the hanger. Accordingly, in mounting the device, the sleeve 17 of the jaw 10 may first be screwed upon the stud 26 for connecting said jaw with the insulator when, after the wires 13 and 24 have been arranged in place, the jaw 11 may be assembled with the jaw 10 and the nuts 22 applied to the nipples 16 for drawing the jaws together and clamping the wires therebetween. In thus forming the jaws so that one jaw may be secured in place while the other jaw may be subsequently assembled with the former jaw, the mounting of the wires will be greatly facilitated. Furthermore, attention is directed to the fact that since the sleeve 17 is open at its ends and is elongated into the barrel portion of the jaw 10 instead of exteriorly thereof, the sleeve may, as shown in Figure 1, be screwed up upon the stud 26 close to the insulator for minimizing the leverage which would otherwise be exerted upon the stud by the hanger.

Having thus described the invention, what I claim is:

- 40 1. In a hanger of the character described, the combination of separate coacting jaws to engage a wire, one of the jaws being provided with means for mounting such jaw upon a support and the other of said jaws being formed for assembly with the former jaw after the former jaw is mounted, and means rotatably adjustable longitudinally of the jaws for drawing the jaws toward each other.
- 50 2. In a hanger of the character described, the combination of coacting jaws to engage a wire, one of the jaws being provided with means for mounting such jaw upon a support and the other of said jaws being separable from the former jaw when mounted, and means rotatably adjustable longitudinally of the jaws for drawing the jaws toward each other and removably connecting the latter jaw with the former jaw.
- 55 3. In a hanger of the character described, the combination of coacting jaws to engage a wire, one of the jaws being provided with a sleeve for mounting such jaw upon a support and the other of said jaws being separable from the former jaw when mounted,

and means rotatably adjustable longitudinally of the jaws for drawing the jaws toward each other and removably connecting the latter jaw with the former jaw.

4. In a hanger of the character described, 70 the combination of coacting jaws to engage a wire, one of the jaws being provided with a sleeve for mounting such jaw upon a support and the other of said jaws being separable from the former jaw when mounted, and means rotatably adjustable longitudinally of the jaws for drawing the jaws toward each other and removably connecting the latter jaw with the former jaw, the latter jaw being provided with a flange fitting about said sleeve.

5. A hanger of the character described including coacting hollow jaws mating to define a barrel and formed to receive a wire therebetween extending through the barrel, 85 and means at the ends of the barrel connecting the jaws with each other.

6. A hanger of the character described including coacting hollow jaws mating to define a barrel and formed to receive spaced 90 wires therebetween one extending through the barrel, and means at the ends of the barrel connecting the jaws with each other.

7. A hanger of the character described including coacting hollow jaws mating to 95 define a barrel and formed with nipple portions mating to define nipples projecting from the ends of the barrel and adapted to receive a wire extending through the barrel between the jaws, and means adjustable longitudinally upon each of said nipples for drawing the jaws toward each other.

8. A hanger of the character described including coacting jaws formed to receive a wire therebetween and mating to define a barrel, one of the jaws being provided with means for connecting such jaw with a support and opening into the barrel, and means connecting the jaws with each other.

9. A hanger of the character described including coacting jaws formed to receive a wire therebetween and mating to define a barrel, one of the jaws being provided with a sleeve opening into the barrel and adapted to receive a supporting element for such jaw, and means connecting the jaws with each other.

10. A hanger of the character described including coacting jaws formed to receive a wire therebetween and mating to define a barrel, one of the jaws being provided with a sleeve opening into the barrel and adapted to receive a support for such jaw and the other of the jaws being formed with a flange to fit said sleeve, and means connecting the jaws with each other.

11. A hanger of the character described including coacting jaws formed to receive a wire therebetween and mating to define a barrel, one of the jaws being provided

with means to coact with a support mounting such jaw, centering means carried by the other jaw to coact with the former jaw and housed in said barrel, and means connecting the jaws with each other.

12. A hanger of the character described including coacting jaws formed to receive a wire therebetween and having barrel portions mating to form a barrel, one of the 10 jaws being provided with means to coact with a support mounting such jaw, centering lugs carried by the other of said jaws at the ends of the barrel portion thereof to coact with the ends of the barrel portion 15 of the former jaw for centering the jaws and locking said jaws against relative movement, and means connecting the jaws with each other.

13. A hanger of the character described including coacting jaws having barrel portions mating to form a barrel and provided in said barrel portions with reinforcing means disposed to accommodate an insulator therebetween extending through the barrel, and means for drawing the jaws toward 25 each other about said insulator.

14. A hanger of the character described including coacting jaws having barrel portions mating to form a barrel and provided in said barrel portions with reinforcing webs notched to fit an insulator extending 30 between the webs through the barrel, and means for drawing the jaws toward each other about said insulator.

In testimony whereof I affix my signature.

ALBERT J. GURNEY. [L.s.]
